(57) **CLAIM**

The ornamental design for a vacuum hose end, as shown and described in FIGS. 1-7.

DESCRIPTION

FIG. 1 is a top perspective view of the design of the present disclosure;

FIG. 2 is a right side view of the design depicted in FIG. 1; FIG. 3 is a left side view of the design depicted in FIG. 1; FIG. 4 is a rear view of the design depicted in FIG. 1; FIG. 5 is a front view of the design depicted in FIG. 1; FIG. 6 is a top view of the design depicted in FIG. 1; and, FIG. 7 is a bottom view of the design depicted in FIG. 1. Those portions of the present invention which are presented in phantom illustrate the environment of the design only and form no part of the claimed design. Moreover, the shading presented in the accompanying drawings is provided merely to highlight the contour of the invention and is not intended to be illustrative of texture or gloss.

1 Claim, 5 Drawing Sheets
